SHINGLE

Norman P. Harshberger, Scarsdale, N. Y., assignor to Bakelite Building Products Co., Inc., New York, N. Y., a corporation of Delaware

Application October 10, 1932, Serial No. 636,973

13 Claims. (Cl. 108—7)

This invention relates to improvements in shingles, and the present application is a continuation in part of application Serial No. 484,077.

In the composition shingle industry, individual shingles are recognized to possess certain advantages over the strip shingle because of the fact that a greater degree of overlap and protection is afforded, and because of the fact that a roof assembled from a plurality of individual shingles is usually more attractive than one built up from elongated strips. Strip shingles, however, have advantages over individual shingles because assembly can be effected in substantially less time, thus materially reducing the cost of installation.

It is one of the objects of this invention to provide shingles which are so interconnected during manufacture as to provide for compact stacking, and for quick conversion of the shingles from individual stack formation to strip formation in which each strip comprises a plurality of interconnected elements.

Another object of the present invention is to combine the advantageous features of strip and individual shingles, by providing individually cut units which may be pre-assembled in overlapping strip formation during the process of manufacture to thus facilitate the assembly on the roof.

A further object of the invention is to provide individual shingles so interconnected during manufacture that they may be swung relative to one another in parallel planes to provide for compact packaging in the same manner as a plurality of individual shingles would be packaged.

A further object of the invention is to provide shingles of the class described which may be manufactured with surfacing on both sides to permit reversal during assembly.

With the above and other objects in view, the invention consists of the improved shingle and all its parts and combinations as set forth in the claims, and all equivalents thereof.

In the accompanying drawing, illustrating one complete embodiment of the preferred form of the invention, in which the same reference numerals designate the same parts in all of the views:

Fig. 1 is a plan view showing a pair of pre-assembled individual units;

Fig. 2 is a plan view showing a plurality of the shingles of Fig. 1 as they appear in assembled relation;

Fig. 3 is a plan view showing four individual elements pre-assembled in strip form;

Fig. 4 is a perspective view illustrating the

manner of swinging the individual portions of the strip of Fig. 3, for packaging purposes; and

Fig. 5 is a cross sectional view taken through a pack of the type illustrated in Fig. 4.

Referring more particularly to the drawing, it will be seen that in Fig. 1 it was preferred to illustrate diamond shaped shingles constructed in accordance with the teachings of the present invention. The said shingles may have one lower corner provided with foldable portions 8 and 9, the portion 8 being adapted to receive a nail in assembly. When the fold is utilized on the lower corner, the upper corner of each unit may be cut off as indicated by the numeral 10.

The important feature of the present invention resides broadly in the pre-assembly of a plurality of individual units in connected and/or in overlapping relation, and with the diamond shaped unit illustrated in Figs. 1 and 3, adjacent corners may be overlapped a desired distance, and the said corners are preferably secured together in a permanent manner by any suitable means. The particular manner of securing the corners together, which is illustrated in the present case, results in additional advantages which will be hereinafter described.

The amount of overlap can, of course, be varied at will, and by making the overlap as small as possible, more economical coverage of a roof may be obtained. On the other hand, by having a substantial overlap as illustrated, the degree of protection is increased with, however, an increase in expense.

The shingles may be assembled either diagonally or in the manner shown in Fig. 2, a nail 11 being driven into the fold portion 8 at the lower corner, and the lower corner of the shingle being pulled down to cover said nail in the manner fully described and claimed in application Serial No. 484,077. The ends of adjacent strips are overlapped a distance equal to the permanent overlapping of the individual sections. After a course, or a portion of a course, has been laid, the next succeeding course is laid thereabove in such a manner that the lower part thereof just bridges a part of the recess formed between the tabs of two elements of the course below to produce hexagonal figures. By surfacing each unit on both sides, each side with a different color mineral, certain of the strips can be reversed during assembly to produce a two color effect, or all of the strips may be reversed to thus make it possible to provide a selection of one of two colors. In addition to reversal of the sur-

faces, the upper and lower edges may be reversed if desired.

Any number of the individual units may be permanently connected together during manufacture, and in Fig. 1 strips are shown which comprise only two individual sections, while in Fig. 3 a strip is illustrated which consists of four interconnected and overlapping sections.

While the broad concept of the invention, as before stated, contemplates the connection and/or overlapping of a plurality of individual units and the securing of said units during manufacture in overlapped position, and while this securing may be accomplished by any desired means, the form particularly illustrated, which consists of a rivet-like member 12, is preferred. This rivet is inserted in such a way as to permit a swinging movement of one individual unit to superimposed position on an adjacent unit in the manner illustrated in Figs. 4 and 5. With this arrangement, strip shingles may be very compactly packed or packaged, and when the strips are being assembled on the roof, it is merely necessary to take the individual packs shown in Fig. 4 and to swing the sections into strip form, as shown in Fig. 3. Thus, all the advantages and conveniences in packing of the individual shingle are present, and at the same time, the assembly on the roof is expedited due to the strip shingle form. Other forms of connection than the rivet may be utilized with or without permanent overlap to permit conversion from stack form to connected strip form.

It is to be understood that while the invention is shown as applied to cut units of substantially diamond shape, that it may be utilized in connection with shingles of any desired form, and it is to be understood that all changes, modifications and adaptations are contemplated as may come within the scope of the claims.

40 40. What I claim is:

1. Connected overlapping shingles comprising a plurality of individually cut units having unlike faces and secured together during manufacture by means providing for swinging movement of the individual units relative to one another with said unlike faces in juxtaposed relation and with said means wholly within the edges of the connected overlying unit.

2. Shingles comprising a plurality of individually cut units secured together in overlapping relation during manufacture by means providing for swinging movement of the individual units relative to one another with said means wholly within the edges of the connecting overlying unit.

55 3. Shingles comprising a plurality of individually cut units riveted together in overlapping relation during manufacture to provide for swinging movement of the individual units relative to one another with unlike faces of the shingles abutting.

60 4. Shingles comprising a plurality of individually cut units secured together during manufacture by means providing for swinging movement of the individual units relative to one another in substantially parallel planes.

5. Shingles comprising a plurality of individually cut units having adjacent corners secured together during manufacture by means providing for swinging movement of the individual units relative to one another, said means spaced wholly 5 within the edges forming said corners.

6. The method of packing shingles comprising swingably securing a plurality of individual shingles in assembled relation to one another, and moving said shingles relative to one another to 10 form a stack in which each shingle completely overlies the one below and in which all similar faces of the shingles face in the same direction.

7. Shingles comprising a plurality of individually cut permanently end connected units adapted 15 to be relatively displaced to stack the units in substantially aligned relationship with all similar faces of adjacent elements disposed in the same direction.

8. Shingles comprising a plurality of individually cut units interconnected in groups during manufacture and hinge connecting means secured to adjacent elements and providing for swinging movement of the units relative to one another in parallel planes and adapting the units of each 25 group to compact stacking in superimposed relationship and for conversion into end connected strip form.

9. Shingles comprising a plurality of units, means for securing together adjacent units during manufacture in overlapping relation, said means providing a swinging movement of the units relative to one another in substantially parallel planes.

10. Connected shingles comprising a plurality 35 of elements, means wholly within the edges of the elements for securing together said elements in overlapping relation and providing for a swinging movement of the units relative to one another, said means comprising a point connection. 40

11. Shingles comprising a plurality of units having defining edges, means wholly within said edges securing together said units during manufacture in overlapping relation and providing for a swinging movement of the units relative to one another, said means comprising a connected pivot 45 normal to the face of the unit.

12. Connected shingles comprising a plurality of elements secured together during manufacture in overlapping relation and provided with means 50 to swingably adjust the elements relative to one another in substantially parallel planes, said means comprising a freely rotating hinge connection between adjacent elements.

13. In a shingle stack, a plurality of individual 55 shingles in assembled relation to one another with all similar faces of adjacent shingles facing in the same direction and means permanently securing together adjacent elements in the stack, said means allowing a swinging movement of the 60 shingles relative to one another to form a connected strip of overlapping elements when laid upon a surface.
